CLAIM

The ornamental design for a weight case, as shown and described.

DESCRIPTION

FIG. 1 is a view in front elevation of the weight case of this invention;

FIG. 2 is a view in rear elevation;

FIG. 3 is a bottom plan view;

FIG. 4 is a top plan view; and,

FIG. 5 is a view in end elevation, the other end being a mirror image.

The broken line showing of the weight-receiving cavities in FIG. 1 merely illustrates that the interior of the case is visible through the transparent front surface and forms no part of the claim design.
